(57) CLAIM

The ornamental design for a surgical tibial retractor tool, as shown and described.

DESCRIPTION

FIG. 1 is a right side elevational view of a surgical tibial retractor tool showing my new design, the left side being the mirror image of that shown;

FIG. 2 is a top plan view thereof;

FIG. 3 is a rear elevational view thereof; and,

FIG. 4 is an isometric view of the tibial retractor tool.
